[57] CLAIM

The ornamental design for a hood for a lawn and garden tractor, substantially as shown and described.

DESCRIPTION

FIG. 1 is a side elevational view of a hood for a lawn and garden tractor showing my new design, the opposite side being a mirror image thereof;

FIG. 2 is a top plan view thereof;

FIG. 3 is a front elevational view thereof; and

FIG. 4 is a side elevational view thereof, in an open position. The portion of the tractor shown in broken lines in FIGS. 1 and 4 is for illustrative purposes only and forms no part of the claimed design.

FIG. 1
